United States Patent Office.

WILLIAM R. WALLIS, OF ALLIANCE, OHIO.

Letters Patent No. 65,779, dated June 11, 1867.

IMPROVED METHOD OF ATTACHING EAVE-TROUGHS TO HOUSES.

The Schedule referred to in these Letters Patent and making part of the same.

TO ALL WHOM IT MAY CONCERN:

Be it known that I, WILLIAM R. WALLIS, of Alliance, in the county Stark, and in the State of Ohio, have invented certain new and useful improvements in Attaching Eave-Gutters to Houses; and do hereby declare that the following is a full, clear, and exact description thereof, reference being had to the accompanying drawings, and to the letters of reference marked thereon.

In the annexed drawings, making part of this specification, A represents the eaves-trough, provided with the usual bead B. C represents a strap of metal which runs across the top of the trough, with one end curved or bent around the bead. D represents a metallic strap which is riveted at a to the strap C, and bending around or over the bead, passes under the trough and is bent over its edge on the other side, (side next to the eave,) and this end is caught between the strap C and a plate, E. F represents a thumb-screw which passes through the plate E and through the strap C. This thumb-screw serves to press and bind the plate E and strap C together, securing the end of strap D between them. H represents the hanger, one end of which is properly secured upon the roof of the building with nails or screws. The lower end of this hanger is corrugated, as represented, and provided with two or more slots which run crosswise of it. G represents a metallic strap, one end of which is riveted to the strap C. It is bent at right angles to said strap, as seen, and its upper end, after being passed through the slots in the hanger H, is bent down so as to suspend the trough in the manner shown. By means of the strap G the trough may be secured closer to or further from the eave, as the case may require. By means of the thumb-screw F and plate E the end of strap D may be so confined as to narrow or widen the trough.

Having thus fully described my invention, what I claim as new, and desire to secure by Letters Patent, is—

The strap D, when used in combination with the strap C and plate E, with its thumb-screw F, as and for the purpose herein set forth.

In testimony that I claim the foregoing, I have hereunto set my hand and seal this 11th day of February, 1867.

WILLIAM R. WALLIS.
